DISPENSING CONTAINER

Lewis E. Kirkwood and Harry W. Bull, Midland, and David D. Cornell and Kenneth T. Buttery, Kalamazoo, Mich., assignors to The Dow Chemical Company, Midland, Mich., a corporation of Delaware

Filed May 9, 1962, Ser. No. 70,051

Term of patent 14 years

(Cl. D58—12)

FIGURE 1 is an isometric view of a dispensing container showing our new design, wherein the cut-away portion is located eccentrically of the median line; and

FIGURE 2 is an isometric view of a modified form of a dispensing container showing our new design wherein the cut-away portion is centrally located.

The essential features of our design are indicated by solid lines and reside in the configuration of a container construction having an overlapping front flap which is interrupted intermediate of its lateral ends by a cut-away portion of approximately one-third the width of the flap and in communication with the bottom of said flap, the flap extending generally longitudinally across the front of the container.

We claim:

The ornamental design for a dispensing container, as shown and described.
